UNITED STATES PATENT OFFICE.

LEWIS C. MYERS, OF FREEPORT, AND GEORGE F. HANDLEY, OF GLENDALE, NEW YORK,
ASSIGNORS TO ROYAL TYPEWRITER COMPANY, INC., OF NEW YORK, N. Y., A COR-
PORATION OF NEW YORK.

TYPEWRITING MACHINE.

Application filed April 29, 1926. Serial No. 105,562.

This invention relates to a support for the entire shift frame which is made adjustable on the main frame in order that the position of the platen may be determined accurately with reference to the impression of the entire face of the type bars. It is illustrated as applied to a small portable machine of very compact construction, but may be embodied in other types of machines. It is particularly in the nature of an improvement upon the construction shown in the patent to Myers and Handley, 1,562,119, November 17, 1925.

An object of the invention relates to the provision of means whereby when the entire shift frame is shifted for the purposes of adjustment, as above mentioned, the shift key lever and counter balance spring will be adjusted as a unit therewith in order to preserve the proper relationship between these parts. The advantages of such a construction will be apparent from the following detailed description.

In the drawings:

Figure 1 is a vertical fore and aft section with parts in elevation of a typewriting machine embodying the invention.

Figure 2 is a side view of one of the adjustable members detached from the machine.

Figure 3 is a fragmentary side elevation showing one means for obtaining a fine adjustment of the movable frame.

Figure 4 is a detail section view showing another means of adjustment.

Figure 5 is a section on the line 5—5 of Figure 1 with parts omitted, showing the mounting of the shift frame in the adjustable plates.

Figure 6 is a view corresponding to Figure 1 but showing a different form of platen shift lock mechanism.

Figure 7 is a top plan view of one side of Figure 6 with parts omitted.

Figure 8 is a side view of a portion of the machine frame.

The invention is disclosed as applied to a typewriting machine having a frame A, platen B, type bars C, which are operated from keys D through any old or desired form of connections and other usual instrumentalities. The type bars when in printing position as shown in Figure 1 are adapted to strike against an abutment E

which limits their movement toward the platen.

The platen is supported in the carriage comprising a lower member 1 having track members 2 and 3 which cooperate with track elements 4 and 5 on the shifting frame 6 by means of anti-friction balls 6 in the usual manner. The track elements 4 and 5 are connected by means including a tie plate 7.

Rockers arms 8 are connected at their forward ends to the rail structure just described and are secured at their other ends to the shaft 9, which at one side of the machine has a depending arm 10 provided with a stud 11 about which engages the hooked end of a link 12 which is connected at its forward end to the upward end of an extension 13 of a member 14, which has a forward extension 15 provided with a shift key 16. Pivoted to this forward extension 15 is a shift lock key 17 held in normal position by the usual spring 18.

To the carriage rail 4 is rigidly secured an arm 19, to the lower end of which is pivoted a link 20 and the other end of this link is pivotally connected by a screw 21 to a shifting plate 22. This parallel link motion is for the purpose of giving the shift frame and platen their proper movement when shifted for upper case characters.

Since the type bars are limited in their movement toward the platen it is necessary in assembling the machine to position accurately the carriage in order that the type imprints can be clear. It is also necessary that this adjustment should be a right line and substantially perpendicular to the position taken by the type bars when in printing position. Such adjustment is attained in the following manner. The plate 22 above mentioned is of course duplicated at each side of the machine and there are provided in the side frame A openings 23 through which extend bent ears 24 of the plate 22. The plate is held in its adjusted position by means particularly shown in Figure 5 from which it appears that the screw 21 threads into the end of a stud 25, the end of which fits into the plate 22. A screw 26 passes through a short slot 26' in the main frame A and also threads into the stud 25. The rock shaft 9 has an adjustable cone bearing 27 threaded into the

end thereof and this cone bears in the correspondingly shaped end of a short hollow stud 28, the other end of which fits into the plate 22, a screw 29 similar to the screw 26 in its form of mounting passing through a short slot 29' the machine frame A into the stud 28.

It is evident from this description that the whole shift frame including the rock shaft 9 and the parallel link construction is supported by the plates 22 and that these plates with the structure supported thereby can be adjusted with reference to the main frame of the machine and are held in the desired adjusted position by tightening the screws 26 and 29. In the form shown in Figure 1, there is no particular means for moving the plates 22 to the desired position. After the screws 26 and 29 are loosened these plates may be moved manually in any manner as by inserting one end of the screw driver in one of the slots 23 and giving the plate the desired movement. When located in the proper position the screws 26 and 29 are again tightened. In some cases, particularly in larger machines, it may be desirable to obtain a more fine adjustment of the position of the plates 22 and the mechanism supported thereby. This may be attained in various ways, two of which are illustrated in Figures 3 and 4.

In the form shown in Figure 3, the plate 22 has an ear 30 offset therefrom, while the frame A has a similar ear 31 and a screw 32 is adapted to revolve idly in the ear 31 but to be threaded into the ear 30. It is evident that by loosening the screws 26 and 29 and turning the screws 32, proper adjustment of the shift frame may be attained. In the form shown in Figure 4, one of the ears 24 of the frame 22 is extended at 33, while the main frame A has an offset ear 34 through which passes a screw 35 which threads into the ear 33 in a manner similar to that just described. The plates 22 also carry means for limiting the movement of the shift frame in its case shift movement. This means comprises two stop screws 36 and 37 adjustably threaded into means 38 and 39 struck up from the plates 22. An ear 40 preferably extending from the member 19, cooperates with these stop screws in the usual manner.

In the form shown in Figure 1 the shift frame is locked in its normal position by means of an adjustable stop screw 41 carried by the lower end of the frame 10 with which engages a bent over end 42 of the member 43 extending from the key actuated member 14.

In the main, the features above described are or may be substantially identical with those disclosed in the above identified patent. It has been found that in such construction when the plates 22 and the shift frame carried thereby are adjustable, the proper rela-

tion between the stop screws 41 and the offset end of the member 42 will be destroyed and that the adjustment of the counter balance spring which is usually employed will also be effected. The main purpose of this invention is to devise means for overcoming these objections and also to provide a construction whereby the adjustable shift frame composed of the plates 22 and the members carried thereby shall also carry the counterbalance spring and the shift key levers with their shift keys. This construction will now be particularly described.

Each plate 22 has a long forward extension 44 provided with a screw 45 which fits in an inclined slot 46 in the side frame of the machine and guides the plate when it is adjusted. The extension 44 also has a depending ear 47 and in these ears is mounted the shaft 48 which carries the rocking frame 14 above mentioned. The extreme forward end of the extension 44 is provided with a pin or stop member 49 which cooperates with a cut out 50 in the shift lock key 17 to hold the same in depressed position in the usual manner.

In the form shown in Figures 6 and 7 there is illustrated a modification of the means for locking the shift frame in normal and shifted positions. In this modification the arm 8 has a short downward extension 51 provided with a stud 52 with which coacts the open hooked end of the link 12, as in the first described form. A depending arm 19 has an offset ear 53 which coacts with the hooked end 54 of a short lever 55 pivoted at 56 to the extension of the plate 22. This lever is connected by a link 57 to the upper end of the extension 13 of the rocking frame 14. When the shift key or shift lock key is first depressed, the initial movement of the rocking frame will pull on the link 57 and move the hook 54 from over the ear 53, thus releasing the shift frame for its shifting movement. The shift lock key 17 has a downward extension 58 which is connected by a link 59 with the lower end of a lever 60, preferably pivoted on the same stud 56 as the lever 55. This has an angular cut out 61 in its upper end which coacts with the ear 53 when the shift frame is moved by depression of the shift lock key. At this time the link 59 is pulled forwardly and the upper end of the lever 60 is accordingly moved rearwardly so that the cut out 61 engages beneath the ear 53 and locks the shift frame in its upper position.

The counterbalance spring 62 is connected at one end of an ear 63 of the arm 8 and at its other end to a stud 64 carried by the plate 22.

It will be obvious from the above disclosure that whenever the plates 22 are moved for the purpose of adjusting the

position of the shift frame the shift key lever, the shift lock key lever, the counter-balance spring, and the means for locking the shift frame in lower and upper position, 5 will all move together with the plates 22. It necessarily follows that when a proper adjustment has once been attained between the various parts of this shiftable frame, that the frame as a whole can be adjusted to bring the platen into proper relation with the type without in any way destroying the adjustment existing between the various elements above specified.

It is obvious that the invention may be applied to shifting mechanisms of different character and embodied in machines of various types without in any way departing from the spirit thereof. Minor details may be changed and the form and dimensions 20 of the various parts modified so that it is to be understood that the invention is limited only by the scope of the appended claims.

We claim:

1. In a typewriting machine embodying a main frame, carriage, and pivoted type bars, the combination of a shift frame supporting the carriage for case shift movement, means for mounting said shift frame for bodily adjustment as a unit relative to the main 25 frame to obtain proper relation between the carriage and the type bars, and shift key levers adjustable with said shift frame to preserve proper relation between said levers and shift frame in all positions.

2. In a typewriting machine embodying a main frame, a carriage, and pivoted type bars, the combination of a shift frame supporting the carriage for case shift movement, means for mounting said shift frame for bodily adjustment as a unit relative to the main frame to obtain proper relation between the carriage and the type bars, and means for locking the shift frame in its lower case position also adjustable with the shift frame to preserve the proper relation 40 of the parts.

3. In a typewriting machine embodying a main frame, a carriage, and pivoted type bars, the combination of a shift frame supporting the carriage for case shift movement, means for mounting said shift frame for bodily adjustment as a unit relative to the main frame to obtain proper relation between the carriage and the type bars, and means for locking the shift frame in its upper case position also adjustable with the shift frame to preserve the proper relation 45 of the parts.

4. In a typewriting machine embodying a main frame, a carriage, and pivoted type bars, the combination of a shift frame supporting the carriage for case shift movement, means for mounting said shift frame for bodily adjustment as a unit relative to 50 the main frame to obtain proper relation be-

tween the carriage and the type bars, and means for giving the shift frame its case shift movement, said means also adjustable with the shift frame to preserve the proper relation of the parts.

5. In a typewriting machine embodying a main frame, a carriage, and pivoted type bars, the combination of a shift frame supporting the carriage for case shift movement, means for mounting said shift frame for bodily adjustment as a unit relative to the main frame to obtain proper relation between the carriage and the type bars, means for giving the shift frame its case shift movement, and means for locking it in its lower case position, both said means being adjustable with the shift frame to preserve the proper relation of the parts.

6. In a typewriting machine embodying a main frame, a carriage, and pivoted type bars, the combination of a shift frame supporting the carriage for case shift movement, means for mounting said shift frame for bodily adjustment as a unit relative to the main frame to obtain proper relation between the carriage and the type bars, and a counterbalance spring also adjustable with the shift frame to preserve the proper relation of the parts.

7. In a typewriting machine embodying a main frame, carriage, and pivoted type bars, the combination of a shift frame supporting the carriage for case shift movement, means for adjusting said shift frame bodily as a unit relative to the main frame to obtain proper relation between the carriage and the type bars, and shift key levers adjustable with said shift frame to preserve proper relation between said levers and shift frame in all positions.

8. In a typewriting machine embodying a main frame, a carriage, and pivoted type bars, the combination of a shift frame supporting the carriage for case shift movement, means for adjusting said shift frame bodily as a unit relative to the main frame to obtain proper relation between the carriage and the type bars, and means also adjustable with the shift frame for locking it in either case position.

9. In a typewriting machine embodying a main frame, a carriage, and pivoted type bars, the combination of a shift frame supporting the carriage for case shift movement, means for adjusting said shift frame bodily as a unit relative to the main frame to obtain proper relation between the carriage and the type bars, and means for locking the shift frame in its upper case position also adjustable with the shift frame to preserve the proper relation of the parts.

10. In a typewriting machine embodying a main frame, a carriage, and pivoted type bars, the combination of a shift frame supporting the carriage for case shift move-

ment, means for adjusting said shift frame bodily as a unit relative to the main frame to obtain proper relation between the carriage and the type bars, and means for giving the shift frame its case shift movement, said means also adjustable with the shift frame to preserve the proper relation of the parts.

11. In a typewriting machine embodying a main frame, a carriage, and pivoted type bars, the combination of a shift frame supporting the carriage for case shift movement, means for adjusting said shift frame bodily as a unit relative to the main frame to obtain proper relation between the carriage and the type bars, means for giving the shift frame its case shift movement, and means for locking it in its lower case position, both of said means being adjustable with the shift frame to preserve the proper relation of the parts.

12. In a typewriting machine embodying a main frame, a carriage, and pivoted type bars, the combination of a shift frame supporting the carriage for case shift movement, means for adjusting said shift frame bodily as a unit relative to the main frame to obtain proper relation between the carriage and the type bars, and a counterbalance spring also adjustable with the shift frame to preserve the proper relation of the parts.

13. In a typewriting machine embodying a main frame, a carriage, and pivoted type bars, the combination of a shift frame supporting the carriage for case shift movement, a pair of members adjustably mounted in the main frame and entirely supporting the shift frame, said members having forward extensions, and shift key levers supported by said forward extensions.

14. In a typewriting machine embodying a main frame, a carriage, and pivoted type bars, the combination of a shift frame supporting the carriage for case shift movement, a pair of members adjustably mounted

in the main frame and entirely supporting the shift frame, said members having forward extensions, means for guiding said forward extensions in the main frame, and shift key levers supported by said forward extensions.

15. In a typewriting machine embodying a main frame, a carriage, and pivoted type bars, the combination of a shift frame supporting the carriage for case shift movement, a pair of members adjustably mounted in the main frame and entirely supporting the shift frame, said members having forward extensions, shift key levers supported by said forward extensions, a shift lock key and a detent therefor carried by a forward extension.

16. In a typewriting machine, the combination of a main frame, type bars, an auxiliary frame supporting a carriage and all case shift instrumentalities, and means for mounting said auxiliary frame for adjustment relative to the main frame to preserve proper relationship between the carriage and typebars.

17. In a typewriting machine, the combination of a main frame, type bars, an auxiliary frame supporting a carriage and all case shift instrumentalities, and means for mounting said auxiliary frame for adjustment relative to the main frame at right angles to the type bar at the end of its movement to printing position to preserve proper relationship between the carriage and typebars.

18. In a typewriting machine, the combination of a main frame, type bars, an auxiliary frame supporting a carriage and all case shift instrumentalities, and means for adjusting said auxiliary frame relative to the main frame to preserve proper relationship between the carriage and typebars.

In testimony whereof, we have hereunto subscribed our names.

LEWIS C. MYERS.
GEORGE F. HANDLEY.
